UNITED STATES PATENT OFFICE

2,308,830

NONOVERFILL DEVICE WITH CENTERING
MEANSOliver O. Rieser, Oak Park, Ill., assignor to The
Richardson Company, Lockland, Ohio, a corpora-
tion of Ohio

Application January 8, 1940, Serial No. 312,909

5 Claims. (Cl. 136—178)

In the Keller Patent No. 2,233,081 dated February 25, 1941, entitled Liquid level control device, there is set forth non-overfill means for an electric storage battery which is simple, inexpensive and efficient. It involves a construction of the cell cover to provide a filler well with a bottom, a tubular extension depending from the bottom to a desired maximum electrolyte level, the extension opening through the bottom for filling purposes. There is a perforation through the bottom external to the tubular extension so as to vent gas collecting in the hollow interior of the cell cover at a higher level than the lower end of the extension; and there is a weight-actuated valve member in the form of a perforated disc located within the well and acting to close the perforation when the filler cap is removed. The bottom of the well is so shaped as to provide a fulcrum for the valve member. Thus when the filler cap is put in place it rocks the valve member so as to open the perforation. Various modifications of this structure are set forth in my cases Serial No. 296,667 and Serial No. 303,296, and the Keller Patent No. 2,261,032 dated October 28, 1941.

The fundamental object of the present invention is the provision of centering means for the valve member of automatically acting character such that the valve member cannot possibly bind against the walls of the well. It will be understood that the opening of the valve is a positive mechanical function, but the closing thereof, when the filler cap is removed, occurs under the influence of gravity. It is an object of my invention to provide a structure in which any factors which might interfere with that closing,—such as frictional binding against the walls of the filler well, or binding or sticking due to the presence of electrolyte wetting the parts or exerting a capillary action thereon,—are eliminated. I shall describe my invention in an exemplary embodiment having to do with the structure of the first Keller application set forth above; but its application to other structures will be apparent to the skilled worker in the art from the teachings herein.

These and other objects of my invention which will be set forth hereinafter or will be apparent upon reading these specifications, I accomplish by that certain construction and arrangement of parts of which I shall now describe the aforesaid exemplary embodiment. Reference is made to the drawing wherein:

Figure 1 is a partial sectional view through a cell and cell cover with the filler cap removed.

Figure 2 is a partial sectional view of the cell cover showing the filler cap in place.

Figure 3 is an elevational view of the filler cap.

In Figure 1, I have shown the walls 1 defining one of the cells of a storage battery case. The cell contains the usual assembly 2 of positive and negative battery plates, and the electrolyte 3. The cell has a cell cover 4 of usual external appearance and shape. The body of the cell cover 10 is hollow, providing a gas collection space above the electrolyte; the usual skirt and flange are shown, so that the cell cover can rest upon a ledge within the cell walls and be held in place with the usual sealing compound. The cell cover is 15 shown as provided with conventional openings for the passage of the terminal posts connected to the plate assembly.

It will be understood that while I have illustrated a cell cover of generally conventional form, my invention is applicable to other types of cell cover. The novel elements which distinguish the invention are confined to the filler well and filler cap.

The cell cover is shown with a filler well 5, the 25 interior walls of which are threaded as at 6 or otherwise prepared for the engagement of a filler cap. The well has a bottom 7 from which depends a tubular extension 8 terminating at a desired maximum electrolyte level. The tubular 30 extension is open for filling purposes through the bottom, which thus assumes an annular form. I provide a perforation 9 (or series of perforations) 35 through the bottom exterior to the tubular extension, for the venting of the gas which collects above the electrolyte level within the hollow interior of the cell cover.

The bottom of the well is, in the embodiment shown, formed in two angularly related planes 40 10 and 11. The meeting line of the two planes forms a fulcrum for a weight operated valve member 13. The valve member is in the form of a washer or perforated disc so that the cell may be filled while the valve member is in place. The plane 10 is larger than the plane 11, so that 45 the fulcrum lies at one side of the center of gravity of the weight-actuated valve member. The valve member thus, unless otherwise actuated, lies against the plane 10; and this plane is the one containing the perforation or perforations 9. Variant constructions could involve the formation of the weight-actuated valve member of irregular cross section to shift its center of gravity if the areas of the planes were equal.

When the filler cap is removed, the weight-actuated valve member will thus close the perfora-

tion or perforations 9. When the cell is filled, or the electrolyte replenished by the addition of water through the tubular extension 8, as soon as the electrolyte reaches the end of the tubular extension it will rise rapidly therein thus giving an overfill signal. The weight of the valve member may be made such as to counterbalance the weight of a column of electrolyte or water of the entire length of the tubular extension, in which event overfilling is prevented, even if the filling is carelessly done. But it is essential for the correct operation of the device, that the weight-actuated valve member come to rest when the filler cap is removed in a position to close the gas venting perforation. In order to prevent any possibility of the valve member sticking against the sides of the well, I provide means in connection with the filler cap to center the valve member each time the filler cap is put into position. Thus, when the filler cap is removed, 20 the weight-actuated valve member will be free to fall to the valve closing position.

The filler cap 12 has the usual finger grip portion and the usual threaded extension for engagement in the filler well. In the form shown, it is provided with an annulus 13a for engagement with the top of the weight-actuated valve member. It also is provided with a conical extension 14 the lower end of which is of such size that it will enter the perforation in the valve member in any possible position of the valve member in the well. The conical configuration of the extension is such that as the filler cap is threaded into position, the valve member, if it is not already centered, will be centered. This relationship is shown in Figure 2, and it will be seen in that figure how the filler cap raises the valve member away from a position in which it closes the perforation or perforations 9. The conical extension as well as the body of the filler cap may be made hollow as at 15; and at the top of the filler cap I provide a gas venting orifice 16. If desired a splash washer 17 may be included in the hollow interior of the filler cap.

Modifications may be made in my invention without departing from the spirit thereof, and as I have hereinabove indicated, it will be in the skill of the worker in the art to adapt these teachings to various styles of devices such as are shown in the copending applications referred to above.

Having thus described my invention what I claim as new and desire to secure by Letters Patent, is:

1. In a cover for electric storage batteries, in combination, a filler well having a bottom, a tubular member open through the filler well and depending therefrom to a desired maximum electrolyte level, the said bottom of the well having a gas vent passageway exterior to said tubular member, a teeter valve in said filler well capable of resting on said bottom, said valve and bottom having confronting surfaces at least one of which is broken to provide

5 a fulcrum for said valve, said valve being actuatable by gravity to a position in which said well and said tubular member constitute a single passageway from said electrolyte level upwardly, a filler cap engageable in said filler well, said teeter valve being actuatable by said filler cap to another position permitting escape of gas into said filler well through said gas vent passageway from a point above the bottom 10 of said tubular member, there being a vent from said filler well to the open air for the escape of gas passing therethrough, said filler cap having a tapered projection thereon for engaging an edge of said teeter valve member to center the same and minimize contact thereof with the walls of said filler well.

2. The structure claimed in claim 1 in which said teeter valve is a substantially washer shaped member, centrally perforated, and in which said centering means comprises a downward extension on said filler cap, at least a portion of which is conical, for engagement in the central perforation in said teeter valve, said extension on said valve cap acting to enforce a position of said teeter valve substantially out of contact with vertical portions of the walls of said filler opening.

3. The structure claimed in claim 1 in which said teeter valve is a substantially washer shaped member, centrally perforated, and in which said centering means comprises a downward extension on said filler cap, at least a portion of which is conical, for engagement in the central perforation in said teeter valve, said extension 30 on said valve cap acting to enforce a position of said teeter valve substantially out of contact with vertical portions of the walls of said filler opening, and in which said teeter valve is substantially flat, the bottom of said well being 35 formed in two angularly related meeting planes, one of which is larger than the other, the said gas vent passageway in the bottom of said filler well being located in the larger of said planes.

4. In a cell cover for an electric storage battery of the class in which there is a non-overfill assembly including an apertured teeter valve which is gravitationally urged to closed position, the combination of a filler cap having a tapered member extending downwardly therefrom, said member being smaller than said aperture and arranged to enter said aperture in said teeter valve to impart movement thereto.

5. In a cell cover for an electric storage battery of the class in which there is a non-overfill assembly including an apertured teeter valve which is gravitationally urged to closed position, the combination of a filler cap having a downwardly extending tapered member arranged to enter the aperture in said teeter valve, the axis of said aperture when said valve is in closed position being hetero-axial with respect to said member, said member, upon entrance into said aperture, moving said teeter valve toward a coaxial position with respect to said member.
